UNITED STATES PATENT OFFICE.

EDWARD ROWE, OF INDIANA, PENNSYLVANIA.

STEAM CONDENSER AND AERATOR.

SPECIFICATION forming part of Letters Patent No. 554,539, dated February 11, 1896.

Application filed May 25, 1895. Serial No. 550,630. (No model.)

To all whom it may concern:

Be it known that I, EDWARD ROWE, of Indiana, in the county of Indiana and State of Pennsylvania, have invented a new and Improved Steam Condenser and Aerator, of which the following is a full, clear, and exact description.

The object of the invention is to provide a new and improved steam condenser and 10 aerator which is simple and durable in construction, arranged to insure a quick condensation of the steam from an engine, and to relieve the latter of back-pressure, and also prevent water from the engine running 15 back into the exhaust-pipe, and to aerate the water of condensation, so as to make it better for use in boilers.

The invention consists of certain parts and 20 details and combinations of the same, as will be fully described hereinafter, and then pointed out in the claims.

Reference is to be had to the accompanying 25 drawings, forming a part of this specification, in which similar characters of reference indicate corresponding parts in all the figures.

Figure 1 is a sectional side elevation of the improvement on the line 1 1 of Fig. 2. Fig. 2 is a sectional plan view of the same on the 30 line 2 2 of Fig. 1. Fig. 3 is a sectional plan view of the distributor on the line 3 3 of Fig. 1; and Fig. 4 is a side elevation of the lower end of the baffle-plate.

The improved condenser and aerator is provided with a steam-distributer A, 35 provided with a conical top A' and a correspondingly-shaped but inverted bottom A², into which extends a pipe B connected with the exhaust of the engine, the said pipe B extending a short distance above the bottom A², 40 as plainly indicated in Fig. 1. From the conical top A' of the distributer A lead a series of short nozzles C extending into the short inlet-pipes D, held in the lower head, E', of a shell E, closed at its upper end by a head E².

It will be seen that exhaust-steam passing 45 from the exhaust-pipe through the pipe B into the distributer A passes from the latter through the several nozzles C upward and 50 through the inlets D into the shell E, thereby causing air to be drawn into the inlets D from the outside and on the under side of the shell,

so that air thus drawn into the shell E is mingled with the steam, and consequently a rapid condensation of the steam takes place 55 within the shell without danger of back-pressure to the engine.

In the shell E are arranged a series of air-pipes F, leading from one head E' to the other head E² and arranged alternately with the 60 air-inlet pipes D. (See Fig. 2.) The pipes F, together with the pipes D, are preferably arranged in a circle, and inside of the said pipes is located a baffle-plate G, made circular and set at its lower end on the head E', to 65 extend at its upper end within a short distance of the top of the head E². The lower end of this baffle-plate G is formed with notches or openings G', so that any water of condensation in the water-pipes of the shell 70 can pass through the said openings to the center of the head E'.

A second set of air-pipes H, and held in the heads E' and E², is arranged within the baffle-plate G, and within this set of air-pipes extends 75 a stack I, attached to the top head, E², and extending with its lower end a suitable distance from the lower head, E', as plainly indicated in Fig. 1. The stack I reaches upward and outward a suitable distance beyond 80 the upper end of the head E², so that the steam not condensed can pass through the said stack I to the outside.

In the lower head, E', and at or near the center thereof, is arranged a drain-pipe J for 85 carrying off the water of condensation, the drain-pipe J being connected by a branch pipe J' with the bottom A² of the distributer A, so as to carry off any water of condensation that may accumulate in the said distributer. 90

A circular pipe K provided with an inlet-pipe K' and connected with a suitable source of air supply—such, for instance, as a pressure blower or pump—is located under the distributer A, and is provided with a series 95 of nozzles K², which extend through the bottom A² of the distributer, through the said distributer and a short distance into the nozzles C, as plainly indicated in Fig. 1. By this arrangement air under pressure may be forced 100 through the nozzles C, so as to insure a ready outflow of the exhaust-steam from the distributer A through the nozzles C.

It will be seen that by forcing compressed

air through the nozzles C by the nozzles K² the exhaust-steam in the distributer is forcibly ejected through the said nozzles C and inlet-pipes D into the shell. This action tends 5 to cause a vacuum in the distributer and consequently in the exhaust - pipe and engine-cylinder, thus relieving the engine of all back-pressure and permitting it to work with greater power. Now it will be seen that by 10 the arrangement described the steam passing from the engine to the distributer A passes from the latter through the nozzles C in the shell E, to be there mixed or mingled with air drawn in by the steam through the inlet-pipes D. Thus the steam is rapidly condensed, and the condensation is aided by the mingled steam and air coming in contact with the pipes F and H, through which circulates 15 atmospheric air. Thus it will be seen that the mingled steam and air first pass upward 20 in the outer part of the shell E, owing to the baffle-plate G, the steam and air then passing from the upper end of the shell downward and within the baffle-plate G and pipes H to 25 finally permit the steam not condensed and air to pass into and out of the stack I.

On the under side of the top A' of the distributer A is arranged an annular flange A³, so that any water of condensation which is 30 thrown up by the engine through the pipe B is caused to flow down the said flange and drop upon the bottom A² without danger of the said water being carried by the exhaust-steam through the nozzles C.

35 Having thus fully described my invention, I claim as new and desire to secure by Letters Patent—

1. A steam condenser and aerator, comprising a shell provided with air-inlets, steam-nozzles extending from a steam-distributer 40 into the said air-inlets, to cause the exhaust-steam passing through the nozzles and air-inlets to draw in the air through the inlets, to insure a mingling of the air and steam within 45 the said shell, and nozzles connected with a compressed-air supply and extending into the said steam-nozzles, substantially as shown and described.

2. A steam condenser and aerator, comprising 50 a shell formed with a series of short air-inlets in its lower head, a steam-distributer connected with a steam-exhaust, a series of steam-nozzles extending from the said distributer into the said air-inlets, and a stack 55 extending into the said shell, substantially as shown and described.

3. A steam condenser and aerator, comprising

ing a shell formed with a series of short air-inlets in its lower head, a steam-distributer connected with a steam-exhaust, a series of 60 steam-nozzles extending from the said distributer into the said air-inlets, and a baffle-plate arranged within the said shell and inside of the said air-inlets, the said baffle-plate extending from the lower head of the shell to 65 within a short distance of the top thereof, substantially as shown and described.

4. A steam condenser and aerator, comprising a shell formed with a series of short air-inlets in its lower head, a steam-distributer 70 connected with a steam-exhaust, a series of steam-nozzles extending from the said distributer into the said air-inlets, a baffle-plate arranged within the said shell and inside of the said air-inlets, the said baffle-plate extending from the lower head of the shell to 75 within a short distance of the top thereof, a stack extending into the shell from above and terminating at its lower end a short distance from the lower head of the shell, substantially 80 as shown and described.

5. A steam condenser and aerator, comprising a shell formed with a series of short air-inlets in its lower head, a steam-distributer connected with a steam-exhaust, a series of 85 steam-nozzles extending from the said distributer into the said air-inlets, a baffle-plate arranged within the said shell and inside of the said air-inlets, the said baffle-plate extending from the lower head of the shell to 90 within a short distance of the top thereof, and a water-drain pipe leading from the lower head of the said shell, substantially as shown and described.

6. A steam condenser and aerator, comprising a shell formed with a series of short air-inlets in its lower head, a steam-distributer connected with a steam-exhaust, a series of steam-nozzles extending from the said distributer into the said air-inlets, a baffle-plate 100 arranged within the said shell and inside of the said air-inlets, the said baffle-plate extending from the lower head of the shell to within a short distance of the top thereof, a water-drain pipe leading from the lower head 105 of the said shell, and a branch pipe leading from the said drain-pipe into the said distributer, substantially as shown and described.
